POLYETHYLENE SHOE COUNTER

Robert J. Marcy, New York, N. Y., assignor to Endicott Johnson Corporation, Endicott, N. Y., a corporation of New York

Application June 17, 1954, Serial No. 437,340

3 Claims. (Cl. 36—68)

This invention relates to a shoe counter composed of molded, solid plastic polyethylene polymer which is resilient and resistant to creasing when incorporated in the heel portion of a shoe.

In present shoe making practice a shoe counter is placed in the heel portion of a shoe to fit the shoe to the heel and the lower part of the ankle of the wearer. The counter is intended to provide and maintain the shape of the rear of the shoe and also to impart a degree of stiffness to cause the shoe to grasp and cling to the heel of the wearer. Prior to this invention the counters which have been generally employed commercially were made of leather or fibre and were relatively stiff and non-resilient. When a force sufficient to deform leather and fibre counters is applied thereto, the counters are permanently distorted and frequently are cracked or broken. Also, counters of this type are adversely affected by water, perspiration and common chemicals and solvents. Thus, when subjected to water they become soft and are readily deformed and distorted and thereafter, when they dry they remain in the distorted shape and become stiff and relatively brittle. This, of course, detracts from the appearance of the shoe and is uncomfortable to the wearer thereof.

In addition to the foregoing disadvantages, counters of leather and fibre are manufactured by a relatively complicated process involving many different operations.

These and other disadvantages in connection with the commercially used leather and fibre counters have long been recognized and many attempts have heretofore been made to solve the problems and to overcome the difficulties, but none of these attempts have proven successful. In this connection, heretofore it has generally been considered necessary to use a relatively rigid or stiff counter since the prior attempts to use flexible or soft counters were unsatisfactory.

It is a primary object of the present invention to overcome the difficulties heretofore encountered and to provide an improved shoe counter which will provide and maintain the shape of the rear portion of a shoe; which, when subjected to bending and crushing forces, will not crack or break or become permanently distorted and will return to its original shape; which will not be adversely affected by water, perspiration and common chemicals and solvents; which when incorporated in a shoe will fit comfortably and will resiliently grip and provide a degree of support to the heel of the wearer; and which can be manufactured in a very simple manner and can be readily incorporated in a shoe.

I have found that the problems and difficulties heretofore encountered can be solved by providing a shoe counter molded from solid plastic polyethylene polymers coming within the range limits hereinafter indicated. Counters made of the hereinafter indicated type of polyethylene retain their shape and are resilient so as to return to shape when deformed and will not crack or break when subjected to unusual bending or crushing forces. In addition, they have a degree of flexibility so as to

2

yield when force is applied thereto, making the counter comfortable to the wearer while, at the same time, having sufficient body to retain the shape of the shoe and to give support and cling to the wearer's foot. Furthermore, counters made of this material are impervious to and unaffected by water, perspiration and common chemicals and solvents and they retain their desirable characteristics even when subjected to wide fluctuations in temperature and other environmental conditions. Such counters have the further advantage that they can be manufactured by the relatively simple operation of injection molding. Additionally, solid plastic polyethylene polymers do not require the use of plasticizing agents which, in time, might deteriorate or change their characteristics.

15 The polyethylene polymers which may be used in making shoe counters in accordance with my invention are polymers of ethylene and are of the type generally disclosed in Patent No. 2,153,553 issued April 11, 1939, to Fawcett, Gibson and Perrin, and may be produced by the method described in that patent. However, there is a wide range of polyethylene polymers extending from gases through liquids, greases, flexible solids to relatively rigid solids and only a selected group of the solid polyethylene polymers are suitable for my purposes. As previously 20 indicated, the polyethylene polymers suitable for my purposes must be capable of retaining their own shape as well as the shape of the shoe when formed into shoe counters; they must be sufficiently flexible to be comfortable but must give support to the shoe and to the wearer; 25 they must be able to withstand bending and crushing forces without cracking or breaking; they must be impervious to and unaffected by water, perspiration and common chemicals and solvents; and must be capable of being molded by injection molding methods.

30 35 The solid polyethylene polymers used in accordance with my invention can best be defined by their melt viscosity or preferably by their melt index determined in accordance with the "Method of Test for Measuring Flow Rates of Thermoplastics by Extrusion Plastometer" established by the American Society of Testing Materials in 40 their bulletin identified as ASTM Designation D1238-52T issued 1952.

The melt index as determined by the procedure established by the American Society of Testing Materials is 45 the recognized standard in the polyethylene plastics industry for determining and controlling the characteristics of polyethylene polymers and persons skilled in this art are familiar with and use this standard. The melt index is determined by placing the polyethylene polymers 50 in a cylinder having a bore of 0.3760 ± 0.0003 " having an orifice which is 0.0825 ± 0.0002 " in diameter and 0.315 ± 0.001 " in length at the lower end thereof. The polyethylene material is heated to a uniform temperature of 190.0 ± 0.4 ° C. and a weighted piston having a land 55 which is 0.3730 ± 0.003 " in diameter and 0.250 ± 0.005 " in length and weighing 2160 ± 10 gms. is placed in the cylinder above the polyethylene material. The extrudate resulting from the first few minutes of operation is discarded. Thereafter, the resulting extrudate is timed and 60 measured or weighed. The melt index is the flow rate of the extrusion under the above conditions reported in grams per ten minutes of operation.

I have found that polymers of ethylene having a melt index, determined as explained above, of from 200 65 down to 0.33, are satisfactory in the molding of shoe counters in accordance with my invention. Polyethylene polymers having a melt index of more than 200 have been found to be too soft for this purpose while polyethylene polymers with a melt index of less than 0.33 are not satisfactory and cannot be practically molded by injection molding methods. The following 70 table sets forth a group of representative polyethylene

polymers of varying melt indexes within the specified range and also indicates melt viscosity and other characteristics of the material.

TABLE I

Poly- ethylene Polymer	Melt Index, gm./10 min. @ 190° C. (ASTM 1. D-1238-52T)	Viscosity, poises @ 190° C.	Tensile, p. s. i. (ASTM 1. D-412)	Percent Elonga- tion	Percent Brittle Temp. Index Deg. C. (ASTM 1. D-746-51T)
I	200	5×10^2	(2)	(2)	(2)
II	50	19×10^2	(2)	(2)	(2)
III	12	78×10^2	(2)	(2)	(2)
IV	3.6-2.5	32×10^2	1,600	600	-100
V	2.4-1.5	47×10^2	1,750	625	-100
VI	1.5-1.0	73×10^2	1,900	650	below -100
VII	0.99-0.53	13×10^4	2,050	675	below -100
VIII	0.52-0.33	22×10^4	2,300	675	below -100

¹ American Society for Testing Materials.

² Not determined.

It will be noted that the polyethylene polymers that can be used in accordance with my invention have a melt viscosity at 190° C. of between 5×10^2 and 22×10^4 poises.

The polyethylene polymers having the higher melt index are relatively softer and have less tensile strength while the polyethylene polymers having the lower melt index are relatively stiffer and have higher tensile strength. The higher melt index polyethylene polymers may be used satisfactorily in making shoe counters for children's and women's shoes. However, for work shoes and heavy duty shoes it is preferable to use polyethylene polymers with a melt index toward the lower end of the range.

In making the shoe counters I prefer to use the polyethylene polymers within the indicated range in unadulterated form. However, a limited amount of fillers may be incorporated in the polyethylene polymers prior to molding. Fillers which may be employed include mineral fillers such as chalk, carbon black and wood flour; resinous fillers such as thermoplastic terpene resins; and rubber materials such as polyisobutylene. The fillers should not substantially exceed approximately 33 1/3 % by weight of the mixture and this may be increased slightly towards the lower end of the melt index range.

The polyethylene polymers selected from within the indicated melt index range and either with or without the indicated fillers are molded into shoe counters in injection molding machines in accordance with standard injection molding procedure.

The following are specific examples of commercial ethylene polymers which have been molded to form counters of this invention. It will be understood that the following examples are for the purpose of illustration only and are not intended to be limitative upon the scope of this invention:

Example I

The polyethylene resin DYL_T, a commercial polyethylene resin available from Bakelite Co. of New York, N. Y. and having a melt index of 200 was molded into shoe counters having a tough, flexible, resilient, upright wall.

Example II

The polyethylene resin DXL-14, available from Bakelite Co. of New York, N. Y. and having a melt index of 50 was molded into shoe counters having a tough, flexible, resilient upright wall.

Example III

The polyethylene resin DXM-60, available from Bakelite Co. of New York, N. Y. and having a melt index of 12 was molded into shoe counters having a tough, flexible, resilient, upright wall.

Example IV

The polyethylene resin DYNF, a commercial polyethylene resin available from Bakelite Co. of New York, N. Y. and having a melt index of 3.6-2.5 was molded into shoe counters having a tough, flexible, resilient, upright wall.

Example V

The polyethylene resin Alathon 10, a commercial polyethylene resin available from E. I. du Pont de Nemours of Wilmington, Delaware, and having a melt index of 2.6-1.6 was molded into shoe counters having a tough, flexible, resilient, upright wall.

Example VI

The polyethylene resin DYNH.1, a commercial polyethylene resin available from Bakelite Co. of New York, N. Y. and having a melt index of 2.4-1.5 was molded into shoe counters having a tough, flexible, resilient, upright wall.

Example VII

The polyethylene resin DYNH.2, a commercial polyethylene resin available from Bakelite Co. of New York, N. Y. and having a melt index of 1.5-1.0 was molded into shoe counters having a tough, flexible, resilient, upright wall.

Example VIII

The polyethylene resin DYNJ, a commercial polyethylene resin available from Bakelite Co. of New York, N. Y. and having a melt index of 0.99-0.53 was molded into a shoe counter having a tough, flexible, resilient, upright wall.

Example IX

The polyethylene resin DYNK, a commercial polyethylene resin available from Bakelite Co. of New York, N. Y. and having a melt index of 0.52-0.33 was molded into a shoe counter having a tough, flexible, resilient, upright wall.

The shoe counters in the above examples vary in flexibility and stiffness in accordance with melt index of the polyethylene polymers. Thus the higher melt index polyethylene polymers produce relatively more flexible and softer counters and the lower melt index polyethylene polymers produce relatively stiffer counters.

In the accompanying drawings I have shown specific illustrations of shoe counters embodying my invention and I have also shown the counters incorporated in shoes. Thus:

Fig. 1 is a perspective view of a polyethylene shoe counter of this invention;

Fig. 2 is a longitudinal vertical section through the heel portion of a shoe embodying a counter of my invention;

Fig. 3 is a perspective view of a counter according to my invention showing the same in deformed condition in full lines, and in normal position in dotted lines;

Fig. 4 is a perspective view of a shoe, with the heel portion shown in full lines, embodying my invention;

Fig. 5 is a perspective view of the shoe of Fig. 4 with the heel portion in compressed or deformed position;

Fig. 6 is a lateral section of the shoe of Fig. 4 taken on line 6-6;

Fig. 7 is a lateral section of the compressed shoe of Fig. 5 taken on line 7-7; and

Fig. 8 is a longitudinal vertical section similar to Fig. 2 but showing a modification of the counter of my invention that can be used without a lining.

A shoe counter 10 composed of the polyethylene polymers according to this invention is shown in Fig. 1 having an upright wall 11 formed in a horseshoe shape to terminate in a pair of forward ends 12. The upright wall 11 is shaped to have an outer vertically convex surface 13 and an inner vertically concave surface 14 extending from a top or outer edge 15 to a semi-circular

heel seat flange 16 which is formed inwardly of the counter 10 along the bottom of the wall 11. The heel seat flange 16 extends around inside the U-shaped counter 10 and has a terminus at each of the respective forward ends 12. The curvature of the upright wall provides the counter 10 with curved surfaces in the cuboy areas 17 which, for the purpose of this description, refer to the sides of the counter adjacent the respective forward ends 12.

In Fig. 2 the counter 10 is shown incorporated in a shoe 18 between an outer leather layer 19 and an inner shoe liner layer 20. The counter 10 and the adjacent portions of the leather layer 19 and the liner layer 20 are bonded together by cement, glue or other adhesive which will bond polyethylene to leather as for instance the adhesives disclosed in my copending patent application Serial No. 351,507, filed April 27, 1953, which is a continuation in part of abandoned application Serial No. 217,405, filed March 24, 1951. The adhesive joins the layer 19 to the counter surface 13 and the layer 20 to the counter surface 14 to form a heel or quarter portion 21.

The shoe 18 has a sole 22 which includes an inner sole 23, a middle sole 24 and an outer sole 25. The heel portion 21 is fastened to the inner sole 23. The rear end of the inner sole 23 fits inside the heel portion 21 to overlie a corner 26 which joins the heel seat flange 16 to the upright wall of the counter 10. The flange portion of the heel portion 21 rests on the middle sole 24. A raised heel 27 is attached to the outer sole to complete the shoe 18.

In Fig. 3 a perspective view of the counter 10 shows the back of the counter in two positions. In full lines the counter 10 is shown pressed forwardly and inwardly of the counter. In dotted lines the counter 10 is shown with the wall 11 returned to normal position with the thumb pressure removed. The resilient wall 11 of the counter 10 returns to its original shape after deformation upon release of the compressing force.

The wall 11, though relatively thin, will also return the heel or quarter portion 21 as a whole to shape. The bonds between the counter 10 and the layers 19 and 20 join these parts together as a laminated structure in which the parts complement each other in the use of the shoe. In Figs. 4 and 5 the shoe 18 is shown in perspective view. In Fig. 4 the heel portion 21 is shown in its normal shape and in Fig. 5 deformed and depressed. The sectional view of Figs. 6 and 7 show the laminated structure of the heel portion 21 in the normal and deformed conditions.

The application of pressure severely bends the back of the shoe 18 and folds the heel portion 21 inwardly to form a severe crease 28. After the pressure is released the polyethylene counter returns the parts to their original shape. Figs. 4 and 6 illustrate the condition and shape of the heel portion 21 both before and after deformation. The deformation of the heel portion is permitted by the flexibility of the laminated parts and the return is effected by the resiliency of the counter 10.

The heel portion 21 is returned to shape even if the outer leather layer 19 is stiff and offers resistance to the return to original shape as the counter 10 has sufficient resiliency to overcome the inertia of the layers 19 and 20 in returning to normal position. The polyethylene counter 10 also, in resisting permanent deformation from its original shape, continuously forms the heel portion 21 with the desired shape and causes it to cling to and support the heel of the wearer.

The above-described embodiment of this invention as shown in Figs. 1 through 7 is for the purpose of illustration only. Modifications may of course be made in the counter or other components of the shoe in which it is incorporated without departing from the spirit of the invention. For example, the counter with its desirable characteristics has been described as incorporated in a

leather shoe. It will be readily apparent that this invention can be applied to shoes having components composed of other materials. Also, the counter may be made and assembled with the shoe so as to perform the functions of a lining. For example, shoe 32, made according to this invention, shown in Fig. 8, has an upper 30 with its counter and quarter portion modified so as to eliminate the necessity of a separate quarter lining.

In this modification a counter 31 serving also as a quarter liner, is attached to the upper 30 by a suitable bond. The bond adheres to the outer surface of the counter 31 and to the inner surface of the upper 30. The combination piece or counter 31 has all the usual features of both the counter and the quarter liner of the customary shoe construction plus the additional features of this invention, and is combined with the upper 30 to provide a heel or quarter portion 32 of the shoe 29 corresponding to the portion 21 in the shoe 18. The counter is formed with a shoulder 33 adjacent its bottom periphery to form a heel seat flange 34. The combination piece or counter 31 extends from under the insole of the shoe to the top edge of the upper 30.

The counter 31 provides the heel portion 32 with support and shape. It combines the support and shape-providing qualities of the counter of this invention with a smooth yielding yet tough lining surface providing comfort to the wearer and long life to the shoe.

It will be seen that I have provided an improved shoe counter which overcomes the disadvantages heretofore encountered and which is superior in performance and characteristics and is simple to manufacture and incorporate in a shoe.

Thus the counters are sufficiently flexible to yield when force is applied thereto but are resilient and have sufficient body to provide the proper shape to the heel or quarter portion of the shoe and to maintain that shape over a long period of time even when the shoe is subjected to severe usage. Also they are light in weight and can be molded in relatively thin form so that the shoe is not bulky and fits comfortably. In addition, the counters cling to the heel of the wearer, preventing gapping and thereby improving the appearance of the shoe and also the comfort to the wearer.

The counters have the further advantage that they are impervious to and unaffected by water, perspiration and common chemicals and solvents with the result that the life of the shoe is greatly prolonged and the quarter portion will not become misshapen and uncomfortable to wear. The desirable characteristic of my counters will not be substantially affected by fluctuations in temperature or variations in other environmental conditions. In addition, the counters do not deteriorate with age and, since polyethylene does not require the addition of plasticizers, the undesirable results therefrom are avoided.

A further advantage is to be found in the simplicity of manufacture of my counters. The counters can be made by standard molding, preferably injection molding, methods. The result is that the innumerable operations involved in the manufacture of leather and fiber counters are eliminated and my counters can be made in one simple molding operation. Manufacture by injection molding provides the additional advantage that the counter is initially made in its completed shape or form, with the result that many of the internal stresses and strains, such as those in the heel seat, are avoided when the counter is incorporated in a completed shoe. The molding operation also provides a smooth finished surface and the counter can be made so as to taper smoothly and gradually towards the thin upper and forward edges, and eliminate the skiving marks existing on prior counters.

Lastly, the counter can be incorporated in existing designs of shoes by means of adhesives and the simple procedure as described above.

Due to the characteristics of the polyethylene counter,

it may also be used advantageously as a self liner for the quarter portion of the shoe. When so used, it may be made to simulate the color, grain, texture and general appearance of existing linings.

This application is a continuation-in-part of my copending application Serial No. 223,480, filed April 28, 1951, and my application Serial No. 104,529 filed July 13, 1949, which was copending with my application Serial No. 223,480.

Modifications may, of course, be made in the illustrated and described embodiments of my invention without departing from the invention as set forth in the accompanying claims.

I claim:

1. A shoe counter made of solid plastic polymerized polyethylene having a melt index of between 200 and 0.33 and a melt viscosity at 190° C. of between 5×10^2 and 22×10^4 poises.

2. A counter for inclusion in the quarter portion of a shoe for resiliently retaining the shape thereof comprising a unitary stiffening member composed of solid plastic polymerized polyethylene having a melt index of between 200 and 0.33 and a melt viscosity at 190° C. of between 5×10^2 and 22×10^4 poises, and having an upright side wall portion generally U-shaped from end to end and transversely convex on its outer surface and con-

cave on its inner surface with a horizontal flange formed integrally with the lower edge of the wall portion, the surfaces of said wall and flange being smooth and free of ridges and creases with the polyethylene being tough and being free from internal stresses throughout the member and said member being substantially incapable of moisture absorption and being flexible and resilient and having the characteristic of retaining and re-establishing its shape.

3. A counter for inclusion in the quarter portion of a shoe for resiliently retaining the shape thereof as set forth in claim 2 in which the member is of uniform thickness throughout the major portion thereof and tapers in thickness adjacent the upper and forward edges of the upright wall portion.
